DESIGN FOR A PIANO CASE

Thomas J. Dentz, New York, N. Y., assignor to
Janssen Piano Co., Inc., Brooklyn, N. Y., a cor-
poration of New York

Application January 7, 1938, Serial No. 74,138

Term of patent 3½ years

To all whom it may concern:

Be it known that I, Thomas J. Dentz, a citizen of the United States, residing at the Borough of Manhattan, in the city of New York and State of New York, have invented a new, original, and ornamental Design for a Piano Case, of which the following is a specification, reference being had to the accompanying drawing, forming part thereof.

Figure 1 is a front perspective view of a piano case showing my new design.

Figure 2 is a front perspective view of the same piano case, the view being taken from a higher position and with the music rack in closed position.

Figure 3 is an end perspective view.

What I claim is:

The ornamental design for a piano case, as shown and described.

THOMAS J. DENTZ.
